ABSTRACT

In an apparatus for the continuous casting of metal strip a casting cavity is formed between a rotating casting drum and an oscillating casting shoe, both of which are supported on a common shaft.

APPARATUS FOR THE CONTINUOUS CASTING OF METAL STRIP

In continuous casting of metal strip, the use of a casting wheel which has an endless groove in its periphery, is known in the prior art. To form a casting cavity, said groove is covered throughout a segment of its total periphery by a cooled endless casting belt which is supported and guided by guide rolls. Molten metal is poured into the cavity, solidifies to a strip by its contact with the cooled belt and cooled casting wheel, and is discharged from the apparatus as a continuous strip.

However, the casting belt in such an apparatus wears out relatively quickly and it is difficult to provide a satisfactory seal between the casting belt and the casting wheel.

It is an object of the present invention to avoid the above described difficulties. According to the present invention, a casting cavity is formed between the convex peripheral surface of a cooled cylindrical casting drum and the concave curved surface of a cooled casting shoe, the cylinder and shoe both being supported by shafts having a common axis which also is the center of the cylindrical surface of the casting drum and of the curved surface of the shoe. The casting shoe is flared outwardly at its substantially vertical inlet section to form a trough to receive molten metal, and it extends around almost one quarter of the casting drum in casting direction to end in a substantially horizontal outlet section. The cast strip therefore leaves the apparatus in a substantially horizontal, straight line, without using a casting belt.

In order to provide a casting cavity between the said surfaces, one of the surfaces is U-shaped in transverse cross section and the other surface is straight in transverse cross section. For example, that part of the concave surface of the casting shoe which faces the casting drum may have a U-shaped transverse cross section, while the transverse cross section of the outer wall of the drum is straight. As an alternative design, the transverse cross section of the outer wall of the drum may be U-shaped, while the transverse cross section of that part of the concave surface of the casting shoe which faces the casting drum is straight.

In either case, the part which has the surface of U-shaped cross section provides a channel located between shoulders which contact the surface of the other part while the surface of the channel is spaced therefrom to form the casting cavity. The shoulders are provided with elastic packing rings which seal the edges of the cavity. Lubrication is provided for all contact areas to reduce wear by friction. In a preferred embodiment, the packing rings and the lubrication grooves are located in shoulders formed in the curved wall of the casting shoe.

In the operation of the apparatus as molten metal is poured into the casting cavity, the casting drum is rotated continuously and the casting shoe is oscillated continuously in timed relation thereto, preferably advancing with the drum at the same speed as the drum, and then being retracted at a greater speed.

After the strip leaves the casting machine, it may be rolled for metallurgical improvement and coiled. A temperature equalization chamber to obtain a constant strip temperature may be located between the casting apparatus and the rolling mill.

A preferred embodiment of the invention is shown in the

drawings in which:

FIG. 1 is a partly sectionalized elevation of the casting apparatus and

FIG. 2 is a section on line II-II of FIG. 1.

5 A cylindrical casting drum 3 is mounted for rotation on shafts 2 journalled in a frame 1. The drum is driven by a motor 6 through gears 4, 5. A casting shoe 8 is provided with side plates 7 which are located between the frame 1 and the ends of the casting drum 3 and are pivotally supported on the drum shafts 2. As the casting drum is rotated, the shoe, which forms a casting cavity 9 with the drum, may be oscillated by any suitable means, as by a hydraulic cylinder 10, or an eccentric or the like.

The cavity 9 is formed between the convex cylindrical wall 11 of the drum 3 and the concave curved wall 12 of the casting shoe 8. Coolants flow through channels 14 in the drum and through channels 15 in the casting shoe.

15 The side edges of the casting cavity 9 are sealed by shoulders 13 and packing rings 16 which are located on the outside of the shoulders 13, and thereby reduce friction between the wall 11 and the shoulders 13. The shoulders 13 also have lubrication grooves 17 which are located between the packing rings 16 and the cavity 9 and which help to prevent the escape of metal from the cavity.

20 25 In operation, liquid metal pours from the ladle 19 into the tundish 18, which rests on frame 1. An exit opening 18' of the tundish is located vertically above the flared inlet section 20 of the casting shoe.

The liquid metal is solidified through contact with the 30 35 cooled walls 11 and 12 and the shoulders 13 and forms a strip 21, which leaves the casting apparatus in a substantially horizontal direction along a roller table 22. If desired, the strip may be conducted through a temperature equalization chamber 23 and then through a rolling stand 24 and may thereafter be coiled on a coiler 25.

It will be understood that the invention may be variously modified and embodied within the scope of the subjoined claims.

I claim:

40 45 1. Apparatus for the continuous casting of metal strip comprising a casting drum having a convex casting surface, a casting shoe having a concave curved casting surface, the convex casting surface of the casting drum and the concave casting surface of the casting shoe having a common center of curvature and being spaced to provide a casting cavity therebetween, the casting drum being mounted for rotation and the casting shoe being mounted for oscillation on a common axis which is the center of curvature of said casting surfaces.

50 55 2. The apparatus of claim 1 including means for rotating said casting drum and means for oscillating said casting shoe.

3. The apparatus of claim 1 in which the convex casting surface of the casting drum is a cylindrical surface which is straight in transverse cross section, and the concave casting surface of the casting shoe is U-shaped in transverse cross section.

4. The apparatus of claim 1 in which the side edges of the casting cavity are closed and sealed by shoulders each having an elastic packing ring therein.

5. The apparatus of claim 4 in which the said shoulders each have a lubricating groove therein.
